UNITED STATES PATENT OFFICE

JOHN E. WOODBURY, OF WORCESTER, MASSACHUSETTS

INTAGLIO PRINTING

Application filed July 3, 1931. Serial No. 548,613.

The principal objects of this invention are to provide for the inking and printing of intaglio plates in such a way that illustrations and lettered matter on the same plate can be printed very satisfactorily; to provide for the introduction, between the wiping of the ink from an intaglio printing plate and the printing on the paper, of a step designed to remove some of the ink in the engraved lettering on the plate without removing it from the illustrative matter; to provide means for controlling the amount of ink thus removed; to regulate the blackness of the imprint; to provide means for engaging the intaglio printing plate, after the doctor blade has wiped it, for removing some of the ink from the depressions in the portions in which lettering appears, for the purpose of permitting of the printing of illustrative matter and lettering from the same plate both with clear cut impressions.

Other objects and advantages of the invention will appear hereinafter.

Reference is to be had to the accompanying drawing, in which

Fig. 1 is a side view of a well known type of die intaglio printing press with a preferred embodiment of this invention applied thereto, and

Fig. 2 is a view of a plate to which this invention is applicable.

In printing from intaglio plates, ink is applied to the surface of the plate by thoroughly rolling the same by an ink roll or the like, and thereafter the ink is removed from the flat areas of the plate, leaving the ink in the depressions or cuts. These steps have been performed in several different ways well known in this industry. Where the ink is removed by a doctor blade the depressions are left very full of ink, so that if engraved letters are located in the same plate and treated in the same way, the lettering is left so full of ink that it spreads or sprays over the paper, and as a matter of fact this difficulty has prevented the use of this type of printing very largely.

It is the principal object of this invention to provide for printing from such a plate

having an etched illustrative surface, and also a heading or other letter engraving, and preferably to employ the method in connection with a doctor blade for removing the ink from the lettered and illustrative portion of the plate at the same time.

A preferred machine for carrying out this idea is diagrammatically illustrated in Fig. 1. A machine is shown in which the plate 12 has its engraved surface at the bottom, but the invention can be applied to any printing machine.

In Fig. 2 is shown an intaglio plate 12 having an engraved area 9 composed entirely of illustrative matter, and an area 8 composed entirely of lettering.

The trouble that has been mentioned above is due to the fact that both the lettering and illustrative matter are on the same plate, and the further fact that by wiping the plate by means of a doctor blade the engraved lines are left very full of ink. Plates in many cases are wiped by hand and the operator can wipe them hard or lightly as he sees fit in order to change the sharpness of the imprint, but with a doctor wiped plate this cannot be done.

In this machine the usual counter 10 is employed mounted on a ram 11. This counter is raised by the ram to press a sheet of paper 80 on the counter into contact with the printing plate 12 located under a stationary member 13. This is the printing operation. The printing plate 12 is inked as usual by an inking roller 14 cooperating with a fountain roller 15 which bears on the main fountain roll 16 in the ink fountain 17. The roller 14 is mounted on arms carried by a shaft 18 which shaft vibrates. The ink passes from the roll 16 to the roll 15 constantly and is taken up intermittently by the roller 14 and applied to the plate 12 which passes over the roller 14 for that purpose. The operating means for the plate can be of any desired kind and I have shown a main shaft 20 having an eccentric 21 thereon operating a rod 22, which is yieldingly connected by a spring 23 and poppet 24 with a lever 25 pivoted at 26. This lever is pivotally connected to a link 27 which is pivotally connected direct-

ly to the holder 28 for the plate 12. Suitable guides are provided for guiding the plate holder and plate to move in a straight line from the position shown in full lines in Fig. 1, where the inking starts, to the position shown in dotted lines where there is a slight dwell permitted by the spring 23 and where the printing is done.

On the shaft 20 is a cam 29 operating a roller 30 on a lever 31, which by yielding means, not shown, is kept in contact with the cam. The other end of this lever is provided with the usual trailing doctor blade 32. The cam 29 raises the doctor 32 from the position shown in Fig. 1 before the printing plate 12 reaches that point, and the inked plate is thus cleared of ink on its flat surfaces by the doctor 32 as it passes over it. The ink removed runs down the doctor into the fountain 17. This is the usual practice.

On the shaft 20 is another cam 35 which operates a roller 36 on a short link 37. This short link is pivoted to a lever 38 at the point 39. The lever 38 has an extension provided with a screw 40 bearing against the link 37, so as to hold this roller 36 against the cam 35. This lever 38 is fixed on a shaft 41, and obviously, the roller 36 will act as if it were mounted directly on the lever when the high part of the cam 35 engages it. At other times it acts merely as a loose link and has no effect.

A frame 42 is fixed to the shaft 41 and swings with the arm 38. On this frame is a positively driven clean soft rubber roll 43 which moves up against the printing plate when the cam 35 engages the roll 36 and removes ink from the plate. This roll being of soft rubber really is an offset roller and takes an imprint from the engraved matter over which it passes, which in this case is the lettered area 8 only. It rotates at the surface speed of the plate. By the removal of this much ink, this lettered portion of the plate is prevented from spraying the ink over the paper and thus an accurate and clear print can be secured from the lettered portion of the plate as well as the picture portion.

The whole plate thereafter is wiped again by a second very gentle doctor 44 mounted on an arm 45 operated by the cam 29. On the frame 42 is a doctor blade 46 for cleaning the rubber roll 43. This blade is adjusted to remove all the ink from the surface of the rubber roll 43 constantly as it rotates. The whole unit comprising the members 43 and 46 swings together on the axis 41 and is controlled by the cam 35.

The set screw 40 has for its purpose the very delicate adjustment of the pressure of the roller 43 against the printing surface. This has for its aim the control of the amount of ink removed from the engraved part of the plate, and thereby controls the condition

of the imprint on the paper of the lettering. The second doctor 44 is necessary to clean the surface of the plate after the action of the rubber roll.

The operation will be clear. The plate 12 is driven forward, the roller 14 inks the surface of the plate. The plate then passes over the doctor 32 which removes all the ink except that in the depressions. The plate 12 then passes over the roll 43 which is adjusted by the screw 40 to remove a predetermined amount of ink by delicate contact with the plate to the extent required. This roll is not the full width of the plate and extends only throughout the surface of the engraved lettering on the plate. This is done most conveniently where that lettering is located at one end of the plate, as shown in Fig. 2 but, of course, if it is interspersed in different places on the plate, this roller will have to have raised and lowered surfaces to correspond, or possibly the roller itself will have to be raised and lowered for that purpose. The plate then passes over the doctor 44 which may be only the same width as the roller 43, and then the plate proceeds to the printing position over the counter 10.

In this way, the etched illustrative part of the engraved plate prints as usual and the lettered part is prevented from printing with too much ink on it. The printing from the lettered part of the intaglio plate is regulated finely.

Although I have illustrated and described only one form of the invention I am aware of the fact that modifications can be made therein by any person skilled in the art without departing from the scope of the invention as expressed in the claims. Therefore I do not wish to be limited in this respect but what I do claim is:—

1. The method of printing from an intaglio printing plate, which consists in inking the plate, wiping the surface of the plate by means of a doctor, removing excess ink only from certain parts of the area of the engraved portion of the printing surface, and thereafter cleaning the flat surface of the plate again.

2. The method of intaglio printing which consists in supplying with ink an intaglio plate having both illustrative matter and lettering thereon, cleaning the ink from the flat surface of the plate and thereafter removing a portion of the ink from the lettered portion of the plate preparatory to printing.

3. The method of intaglio printing which consists in inking an engraved plate having a plurality of different kinds of engraving thereon, wiping the ink from the flat surface of the plate, taking ink from one portion of the engraved plate to prevent that portion from printing too strong, and then making the impression from the plate.

4. The method of printing from an intaglio

printing plate, which has an area provided with engraved lines forming an illustration and a separate area having engraved letters thereon, which consists in inking the plate, 5 cleaning the surface of the plate by a doctor, applying a surface to the plate to offset ink from the lettered area of the plate, thus reducing the amount of ink to be transferred to the paper from this area, and again cleaning the flat surface of the plate before printing.

5. The method of printing from an intaglio plate, having a plurality of distinct areas of engraved matter thereon, which consists in inking the whole plate, cleaning the whole surface of the plate and then bringing a surface into moving contact with the plate without slippage for the purpose of removing excess ink from one area on the 20 plate, and then cleaning that area again.

6. In an intaglio printing press, the combination with means for holding the printing plate, which plate is provided with an illustrative area and a lettered area, means 25 for inking the entire surface of the plate, means for removing ink from the entire flat surface of the plate and means for removing a film of excess ink in the lettered part of the plate only.

30 7. In an intaglio printing press, the combination with means for holding the printing plate, which plate is provided with an illustrative area and a lettered area, means for inking the entire surface of the plate, 35 means for removing ink from the entire flat surface of the plate, means for removing a film of excess ink in the lettered part of the plate only, means for again removing the surplus ink from the flat surface of the plate in 40 which the lettered area is located, and means for then printing from the plate.

8. In a printing press, the combination of means for moving the intaglio printing plate, said plate having an area provided with illustrative matter and an area provided with lettering, means for inking the whole plate as it moves, a doctor in the path of the plate for cleaning the flat surface of the plate as the plate moves, a soft roller extending only 45 throughout the width of the area of the lettering, means for causing the roller to engage the lettered surface of the plate and to roll freely as the plate moves by it to offset the pattern of the lettered surface thereon, 50 and means for thereafter cleaning the surface of the plate engaged by said roller.

9. In an intaglio printing press, the combination of an ink fountain, a plate holder, means for moving the plate holder over the 55 ink fountain to receive ink therefrom, a doctor, means for constantly forcing the doctor by spring pressure against the plate to remove the ink from the flat surface of the plate, a pivoted frame, a soft roller carried 60 by said frame and free to rotate, and means 65

for forcing the frame into a position to move the roller into contact under regulated pressure with the plate as the surface of the plate which it is desired to treat passes the roller.

10. In an intaglio printing press, the combination of an ink fountain, a plate holder, means for moving the plate holder over the ink fountain to receive ink therefrom, a doctor, means for forcing the doctor against the plate to remove the ink from the flat surface 70 of the plate, a soft roller free to rotate, means for forcing the roller into contact with the plate, means for thereafter cleaning the surface of the plate, and means on said frame for constantly cleaning the surface of said roller 75 from ink and directing the ink away from the roller.

11. In an intaglio plate treating device, the combination of two doctor blades for cleaning the plate and a pivoted frame between them having a soft surfaced roller thereon, and adjustable means for applying pressure to the roller to determine the amount of ink the roller will remove 80 from the plate.

12. In an intaglio plate treating device, the combination of two doctor blades for cleaning the plate and between them a soft surfaced roller, and adjustable means for applying pressure to the roller to determine the amount of ink the roller will remove 85 from the plate.

In testimony whereof I have hereunto affixed my signature,

JOHN E. WOODBURY.
